J. Edwards
ATTORNEY

UNITED STATES PATENT OFFICE.

EDGAR M. BENHAM, OF NORWOOD, OHIO, ASSIGNOR, BY MESNE ASSIGNMENTS, TO THE MOSLER SAFE COMPANY, OF HAMILTON, OHIO, A CORPORATION OF NEW YORK.

SAFETY DEVICE FOR VAULTS, SAFES, AND THE LIKE.

Application filed August 8, 1923. Serial No. 656,394.

This invention relates to safety devices for vaults, safes and the like, and more particularly to means operable from the interior of the structure for admitting air to a person locked inside of the structure.

At the present day, many persons, principally bankers, are much concerned about being waylaid by burglars and forced into a safe or vault and having the door closed and locked upon them, in which case they are subjected to the danger of being suffocated due to the lack of means for allowing air to enter the structure when it is locked.

The principal object of my invention is to provide a device which is adapted to be associated with a vault, safe or similar structure, and which is operable from the inside of the structure to open an air passageway from the exterior to the interior of the structure without requiring the structure to be unlocked and opened.

A further object of my invention is to provide means of the character described which are not operable from the exterior of the structure.

Other objects of my invention will be in part obvious and in part pointed out hereinafter.

In order that a clearer understanding of my invention may be had, attention is hereby directed to the accompanying drawings, forming a part of this application and illustrating one possible embodiment of my invention.

Referring to the drawings:

Fig. 1 is a sectional view through an enclosing wall of a vault or safe, showing the safety device associated therewith; and

Fig. 2 is a rear end view of the safety device.

Similar reference characters refer to similar parts throughout both views of the drawings.

The safety device consists primarily of an air passageway through one of the enclosing walls of the structure and a plug removably filling the passageway, the plug being removable from the passageway by manual manipulation from the interior of the structure to

open an air passageway from the exterior to the interior of the structure. The plug is not removable from the exterior of the structure.

Referring to the drawings, there is shown an enclosing wall of the structure, such as door wall 1. This wall is provided with an air passageway 2 extending from the exterior 3 to the interior 4. A plug 5 fills this passageway and is removable from the interior of the wall. This passageway and plug may be provided in any shapes desired. In a preferred form, however, the passageway consists of a narrow portion 6 toward the exterior of the wall, a larger portion 7 at the end of the portion 6, and a still larger portion 8 toward the rear of the structure. Portions 6 and 7 may be circular or angular, as desired, but portion 8 is preferably circular and has interior threads 9, which are adapted to engage with exterior threads on a retaining member 10, which is also provided with a handle or hand-grip 11, whereby member 10 may be screwed into or out of aperture portion 8. The plug for the air passageway also comprises narrow portion 12 and larger portion 13, respectively complementary to and adapted to fill the portions 6 and 7 of the air passageway. Extending rearwardly from portion 13 is a circular portion 14, which extends through a suitable aperture 15 in member 10, and has at its outer end an enlarged portion 16 formed by upsetting the inner end of portion 14, and, if desired, in addition, a washer or nut 17.

The operation of the device will be apparent from the above description. Normally, the plug is permanently disposed within the air passageway, filling the same in such a way as to prevent explosives from being fed into the structure. However, should a person be locked inside of the structure and be unable to open the same in the regular way, he may, nevertheless, open the air passageway by merely removing the plug therefrom. In the embodiment shown, to remove the plug, the person unscrews the retaining member 10. Continuation of this operation

will bring the member 10 against the enlarged inner end of the central plug portion, and will draw it out of the air passageway progressively with the removal of the member 10 therefrom. When member 10 has been completely unscrewed, the entire plug may be lifted out of the passageway. The replacement of the plug is accomplished by placing the plug in the passageway and screwing member 10 inwardly on the wall.

The removal of the plug from the passageway from the outside of the wall is prevented by reason of the threaded engagement between member 10 and the wall.

A safety device in accordance with my invention may be applied to vault or safe doors, vestibule doors, to the lining of a vault or safe, or in the top or bottom or sides of such structures.

The device, however, should be conveniently accessible to a person within the structure.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What I claim is:—

1. The combination with a vault wall having a safety aperture therethrough, of an untethered plug disposed in said aperture and completely removable therefrom, and means engaging the plug and having a readily releasable threaded connection with the vault wall, for releasably confining the plug in said aperture.

2. The combination with a vault wall having a safety aperture therethrough, of a plug disposable in said aperture, and a retaining member abutting said plug from the rear and threadedly connected to said vault wall, whereby said plug is releasably confined in said aperture against rearward removal therefrom, said retaining member being rotatable with respect to both the plug and vault wall.

3. The combination with a vault wall having a safety aperture therethrough, of a plug disposable in said aperture, and a retaining member abutting said plug from the rear and threadedly connected to said vault wall, whereby said plug is releasably confined in said aperture against rearward removal therefrom, said retaining member being rotatable with respect to both the plug and vault wall, and interlocking with the plug whereby the plug may be withdrawn from said aperture by means of the retaining member.

4. The combination with a vault wall having a safety aperture therethrough, said

aperture having a rearwardly directed internal abutment, of a plug disposable in said aperture and having a shoulder engageable against said abutment whereby forward movement of the plug in said aperture is limited, and means engaging the plug and having a threaded connection with the vault wall, for releasably confining the plug in said aperture.

5. The combination with a vault wall having a safety aperture therethrough formed with an enlarged portion at the rear of a narrower portion, of a plug conforming in shape to and fitted in said aperture, a retaining member threadedly connected to the vault wall, and an extension on the plug rearwardly of its enlarged portion penetrating said retaining member, said retaining member abutting the enlarged portion of the plug when the retaining member is connected to the wall, limiting rearward movement of the plug in the aperture.

6. In a structure of the character described, a wall having a vent hole therethrough, a plug removably seated in the hole, a separate retainer associated with the plug and in threaded engagement with the wall adjacent the inner end of the hole, and means accessible from the rear of the wall for manipulating said retainer into and out of engagement with the threads in the wall to permit and to prevent removal of the plug from the hole.

7. In a structure of the character described, a wall having a vent hole therethrough, a plug removably seated in the hole, a separate retainer associated with the plug and in threaded engagement with the wall adjacent the inner end of the hole, and means accessible from the rear of the wall for manipulating said retainer into and out of engagement with the threads in the wall to permit and to prevent removal of the plug from the hole, said retainer rotatably encircling the plug.

8. In a structure of the character described, a wall having a vent hole therethrough, a plug removably seated in the hole, a hub associated with the plug and in threaded engagement with the wall adjacent the inner end of the hole, and means accessible from the rear of the wall for manipulating said hub into and out of engagement with the threads in the wall to permit and to prevent removal of the plug from the hole, said hub rotatably encircling the plug, and means on the plug in the rear of the hub limiting rearward movement of the hub relatively to the plug.

9. In a structure of the character described, a wall having a vent hole therethrough, a plug removably seated in the hole, a hub associated with the plug and in threaded engagement with the wall adjacent the inner end of the hole, and means

accessible from the rear of the wall for manipulating said hub into and out of engagement with the threads in the wall to permit and to prevent removal of the plug from the hole, said hub rotatably encircling the plug, said hole having a small front portion, and a larger portion at the rear of the

small portion, and said plug having a small portion seating in the small front portion of the hole, a larger portion seating in the 10 larger portion of the hole.

This specification signed this 4 day of August, 1923.

EDGAR M. BENHAM.
